CLAIM

The ornamental design for a pedal-driven vehicle, as shown and described.

DESCRIPTION

FIG. 1 is a front elevation view of the pedal-driven vehicle embodying the design;

FIG. 2 is a rear elevation view of the vehicle;

FIG. 3 is a side elevation view of the vehicle, the other side elevation view being a mirror image thereof;

FIG. 4 is a top plan view of the vehicle; and,

FIG. 5 is a bottom plan view of the vehicle.
